United States Patent Office

Des. 217,125
Patented Apr. 14, 1970

217,125

BOTTLE

John Segesman, Cascade, Mont., assignor, by mesne assignments, to National Heritage Corporation, Great Falls, Mont., a corporation of Utah

Filed Apr. 7, 1969, Ser. No. 16,633

Term of patent 14 years

Int. Cl. D9—01

U.S. Cl. D9—33

Fig. 1

Fig. 2

Fig. 3

Fig. 4

FIG. 1 is a front elevational view of a bottle embodying my new design;

FIG. 2 is an elevational view looking from the left of FIG. 1;

FIG. 3 is an elevational view looking from the right of FIG. 1; and

FIG. 4 is a rear elevational view thereof.

I claim:

The ornamental design for a bottle, substantially as shown.
